SUCTION CATHETER FLOW REGULATOR OR SIMILAR ARTICLE

James C. Halligan, Radburn, N.J., assignor to Becton,
Dickinson and Company, East Rutherford, N.J., a cor-
poration of New Jersey

Filed Feb. 3, 1964, Ser. No. 78,468

Term of patent 14 years

(Cl. D16—1)

FIG. 1

FIG. 3

FIG. 2

FIG. 5

FIG. 1 is a perspective view of a suction catheter flow regulator or similar article;

FIG. 2 is a side elevational view thereof;

FIG. 3 is an end elevation as seen from the right of FIG. 2;

FIG. 4 is an end elevation as seen from the left of FIG. 2, and

FIG. 5 is a bottom plan view thereof.

I claim:

The ornamental design for a suction catheter flow regulator or similar article, as shown.
